(57) **CLAIM**

The ornamental design for a bicycle bottle cage as shown and described.

DESCRIPTION

FIG. 1 is a perspective view of a bicycle bottle cage mounted on a bicycle frame;

FIG. 2 is a perspective view of the bicycle bottle cage of FIG. 1 holding a bottle;

FIG. 3 is a left side perspective view of the bicycle bottle cage;

FIG. 4 is a left side view thereof;

FIG. 5 is a right side view thereof;

FIG. 6 is a top view thereof;

FIG. 7 is a bottom view thereof;

FIG. 8 is a rear view thereof; and,

FIG. 9 is a front view thereof.

The ornamental design which is claimed is shown in solid lines in the drawings. The broken lines in the drawings comprise contour lines and form no part of the claimed design.

1 Claim, 9 Drawing Sheets
